UNITED STATES PATENT OFFICE

MIGUEL ANGEL PIOTTI, OF NEW YORK, N. Y.

WINDOW SASH

Application filed April 12, 1929. Serial No. 354,556.

This invention relates to new and useful improvements in sashes for windows, and aims to provide a sash of the sliding type, which in the present instance, is equipped with a glass panel frame capable of being rotated within the sash frame in order that the inside and outside of the glass panel may be quickly and without danger washed by one within the building. This obviously therefor, will overcome the necessity of the window washer leaning or disposing himself outside the window frame, which is an ever dangerous procedure.

An important object of this invention is to provide a sash of the foregoing type that is of very simple and inexpensive construction, the same embodying but few parts, and these so co-related as to reduce the possibility of disarrangement to a minimum.

The foregoing and other objects of the invention will be readily apparent to those skilled in the art after a consideration of the following specification and accompanying drawings, wherein:

Figure 1 is a perspective of my improved sash as arranged within a window frame, the glass panel frame of the sash being disclosed as swung to open position, which is a position that may be employed when it is desired to 30 ventilate the room, and this without requiring the raising of the sash.

Figure 2 is a horizontal sectional view through the upper end of the sash frame looking downwardly upon the panel frame when 35 in closed position.

Figure 3 is a fragmentary inside elevation of a window frame equipped with a pair of my improved sashes.

Figure 4 is an enlarged fragmentary view 40 partially in longitudinal section through the upper end of my sash, the panel frame being closed.

Figure 5 is a horizontal section through the 45 upper end of one of the sashes as arranged within the window frame, and looking downwardly upon the rotatable panel frame, the full and dotted line positions thereof clearly indicating the manner in which the panel frame may be completely turned around with- 50 in the sash.

Figure 6 is a horizontal section taken through the upper end of the sash frame, and looking downwardly upon the panel frame, which is in a position reverse to that shown in Figure 2.

Figure 7 is an enlarged fragmentary vertical section through the upper end of my improved sash towards one vertical edge thereof, disclosing the preferred type of pivot bearings provided between the panel frame and the sash frame.

Figure 8 is a similar view taken through the pivotal connection between the upper end of the panel frame and the upper supporting arm between the sash frame and panel frame, disclosing the panel frame in one position within the sash frame, and

Figure 9 is a similar view, disclosing the panel frame in reverse position from that illustrated in Figure 8.

Now having particular reference to the drawings, my novel sash consists of a frame 5 of predetermined dimensions, and adapted for slidable arrangement within the conventional window frame A. This frame 5 is formed at its inner edge and at its rear surface with a inwardly projecting flange 6, see Figures 7, 8 and 9. Mounted within this frame is a similarly shaped glass panel frame 7, within which is arranged and secured in conventional manner the glass panel 8. This panel frame 7 is formed around its entire outer edge and at the outer surface thereof with a rabbet 9 for receiving the flange 6 of the sash frame 5 when said panel frame is in normal position, as illustrated in Figures 7 and 8, and will provide a weather-proof joint between the frames 5 and 7. The dimensions of the panel frame 7 is such as to provide a space between the upper and lower edges thereof and the sash frame 5, also as illustrated in Figures 7, 8 and 9.

The upper and lower inner surfaces of the sash frame 5 are equipped with metal channel strips 10—10, mortised within the frame between the flange 6 and inner surface thereof.

The upper and lower ends of the panel frame 7 at one side of the frame are equipped with ball bearing sockets 11, within each of

which is a ball bearing 12 for running engagement with the respective channel strip of the sash frame 5. This obviously therefor, provides a sliding and swinging joint between the panel frame and said sash frame.

5 At the inner side of the frame 5 and adjacent one vertical edge of the frame there is provided brackets 13—13, to which are loosely pivotally secured the inner ends of a pair 10 of arms 14—14 of a length to enable the outer ends thereof to be loosely pivoted as at 15 to the direct center of the panel frame 7 at its upper and lower edges, as more clearly illustrated in Figure 1. In order to allow the 15 outer ends of these arms to be properly pivoted to the panel frame, said ends thereof are offset inwardly, as disclosed.

The panel frame 7 is equipped at its outer side and at one edge with a suitable pull 20 handle or knob 16 and obviously, whenever it is desired to reverse the position of the panel frame within the sash to facilitate the washing of the outer surfaces of the glass panel, it is only necessary to pull the handle, 25 which will cause the pivotal and sliding movement of the opposite end of the frame within the sash frame 5, as illustrated in Figure 1. By further pushing the panel frame, the reverse position will be brought about, as illustrated in Figures 6 and 9.

In view of the foregoing description when considered in conjunction with the accompanying drawings, it will be apparent that I have provided a novel, simple and highly 35 serviceable window sash that is well adapted for all of the purposes heretofore designated, and even though I have herein shown and described the most preferred embodiment of the invention, it is nevertheless to be understood 40 that minor changes may be made therein without departing from the spirit and scope of the appended claim.

Having thus described my invention, what I claim as new, and desire to secure by Letters- 45 Patent, is:

In a window sash of the character described, a sash frame, a glass panel supporting frame arranged within said sash frame, said sash frame, at its upper and lower sides being 50 provided with inwardly disposed opposed channels extending thereacross, pivot elements mounted on the upper and lower ends of the panel frame adjacent one side thereof and adapted to pivotally and slidably seat in 55 the adjacent channel, and supporting and guiding arms pivotally connected at one end to the upper and lower ends of the panel frame centrally thereof and at their opposite ends to the sash frame, said panel supporting 60 frame adapted to be shifted to a reverse position in the sash frame.

In testimony whereof I affix my signature.
MIGUEL ANGEL PIOTTI.
